Primary Examiner — Shawki S Ismail*Assistant Examiner* — Kazi S Hossain(74) *Attorney, Agent, or Firm* — Locke Lord LLP; Tim Tingkang Xia, Esq.(57) **ABSTRACT**

Inductor device includes first and a second coils. First coil is wound into plural first circles. Second coil is wound into plural second circles. First connection member is coupled to first circle between outermost and innermost sides among first circles located at first area and first circle on outermost side among first circles located at second area. Second connection member is coupled to second circle on outermost side among second circles located at first area and second circle between outermost and innermost sides among second circles located at second area. At least two first circles of first circles are located at first area, and half of first circle of first circles is located at second area. Half of second circle of second circles is located at first area, and at least two second circles of second circles are located at second area.

INDUCTOR DEVICE

RELATED APPLICATIONS

This application claims priority to Taiwan Application Serial Number 108134717, filed Sep. 25, 2019, which is herein incorporated by reference.

BACKGROUND

Field of Invention

The present disclosure relates to an electronic device. More particularly, the present disclosure relates to an inductor device.

Description of Related Art

In the prior art, the winding method of an eight-shaped inductor device causes a large amount of parasitic capacitance between the coils in the inductor device. As a result, the quality factor (Q) of the inductor device is seriously affected.

For the foregoing reason, there is a need to solve the above-mentioned problem by providing an inductor device.

SUMMARY

The foregoing presents a simplified summary of the disclosure in order to provide a basic understanding to the reader. This summary is not an extensive overview of the disclosure and it does not identify key/critical elements of the present disclosure or delineate the scope of the present disclosure. Its sole purpose is to present some concepts disclosed herein in a simplified form as a prelude to the more detailed description that is presented later.

One objective of the present disclosure is to provide an inductor device to resolve the problem of the prior art. The means of solution are described as follows.

One aspect of the present disclosure is to provide an inductor device. The inductor device comprises a first coil and a second coil. The first coil comprises a first connection member. The second coil comprises a second connection member. The first coil is wound into a plurality of first circles, and the second coil is wound into a plurality of second circles. The first connection member is coupled to the first circle between an outermost side and an innermost side among the first circles that are located at a first area and the first circle on an outermost side among the first circles that are located at a second area. The second connection member is coupled to the second circle on an outermost side among the second circles that are located at the first area and the second circle between an outermost side and an innermost side among the second circles that are located at the second area. At least two first circles of the first circles are located at the first area, and half of the first circle of the first circles is located at the second area. Half of the second circle of the second circles is located at the first area, and at least two second circles of the second circles are located at the second area.

Therefore, based on the technical content of the present disclosure, the inductor device according to the embodiments of the present disclosure can effectively reduce the parasitic capacitance between the coils of the inductor device so as to allow the inductor device to have a better quality factor (Q). In addition, the frequency where the self-resonant frequency (Fsr) of the inductor device occurs

2

is effectively improved to move the frequency where the self-resonant frequency occurs to a higher frequency, thus reducing the influence on the quality factor.

It is to be understood that both the foregoing general description and the following detailed description are by examples, and are intended to provide further explanation of the invention as claimed.

BRIEF DESCRIPTION OF THE DRAWINGS

The accompanying drawings are included to provide a further understanding of the invention, and are incorporated in and constitute a part of this specification. The drawings illustrate embodiments of the invention and, together with the description, serve to explain the principles of the invention. In the drawings,

FIG. 1 depicts a schematic diagram of an inductor device according to one embodiment of the present disclosure;

FIG. 2 depicts a schematic diagram of an inductor device according to another embodiment of the present disclosure;

FIG. 3 depicts a schematic diagram of an inductor device according to still another embodiment of the present disclosure; and

FIG. 4 depicts a schematic diagram of experimental data of an inductor device according to one embodiment of the present disclosure.

According to the usual mode of operation, various features and elements in the figures have not been drawn to scale, which are drawn to the best way to present specific features and elements related to the disclosure. In addition, among the different figures, the same or similar element symbols refer to similar elements/components.

DESCRIPTION OF THE EMBODIMENTS

To make the contents of the present disclosure more thorough and complete, the following illustrative description is given with regard to the implementation aspects and embodiments of the present disclosure, which is not intended to limit the scope of the present disclosure. The features of the embodiments and the steps of the method and their sequences that constitute and implement the embodiments are described. However, other embodiments may be used to achieve the same or equivalent functions and step sequences.

Unless otherwise defined herein, scientific and technical terminologies employed in the present disclosure shall have the meanings that are commonly understood and used by one of ordinary skill in the art. Unless otherwise required by context, it will be understood that singular terms shall include plural forms of the same and plural terms shall include the singular. Specifically, as used herein and in the claims, the singular forms "a" and "an" include the plural reference unless the context clearly indicates otherwise.

FIG. 1 depicts a schematic diagram of an inductor device **1000** according to one embodiment of the present disclosure. As shown in the figure, the inductor device **1000** includes a first coil **1100** and a second coil **1200**. The first coil **1100** is wound into a plurality of first circles **110**. In addition, the second coil **1200** is wound into a plurality of second circles **210**. The first coil **1100** includes a first connection member **1110**, and the second coil **1200** includes a second connection member **1210**.

As for the structure, at least two first circles of the first circles **110** are located at a first area **100** (such as an upper half area in the figure). Half of the first circle of the first circles **110** is located at a second area **200** (such as a lower

half area in the figure). In other words, most of the circles in the first circles **110** of the first coil **1100** are located at the first area **100**. Additionally, at least two second circles of the second circles **210** are located at the second area **200** (such as the lower half area in the figure). Half of the second circle of the second circles **210** is located at the first area **100** (such as the upper half area in the figure). In other words, most of the circles in the second circles **210** of the second coil **1200** are located at the second area **200**. The first connection member **1110** is coupled to the first circle between an outermost side and an innermost side among the first circles that are located at the first area **100** and the first circle on an outermost side among the first circles that are located at the second area **200**. For example, the first connection member **1110** is coupled to a connection point **1111** of the first circle that is located at the first area **100** and located at a middle of three circles among the first circles **110** and a connection point **1113** of the first circle that is located at the second area **200** and on the outermost side among the first circles. In addition to that, the second connection member **1210** is coupled to the second circle on an outermost side among the second circles **210** that are located at the first area **100** and the second circle between an outermost side and an innermost side among the second circles that are located at the second area **200**. For example, the second connection member **1210** is coupled to a connection point **1211** of the second circle that is located at the first area **100** and on the outermost side among the second circles and a connection point **1213** of the second circle that is located at the second area **200** and located at a middle of three circles among the second circles. In one embodiment, the above first connection member **1110** and second connection member **1210** can be coupled to the connection points **1111**, **1113**, **1211**, **1213** correspondingly through vias.

In one embodiment, part of the first connection member **1110** and part of the second connection member **1210** overlap. In another embodiment, the first connection member **1110** and the second connection member **1210** are located on different layers. However, the present disclosure is not limited to the above embodiment.

In another embodiment, the first coil **1100** and the second coil **1200** are located on a same layer. In addition, the first connection member **1110**, the first and second coils **1100**, **1200**, and the second connection member **1210** are respectively located on a first layer **310**, a second layer **320**, and a third layer **330**. Additionally, the first layer **310**, the second layer **320**, and the third layer **330** are sequentially stacked. In other words, the first connection member **1110** is located on an uppermost layer, the first and second coils **1100**, **1200** are located on a middle layer, and the second connection member **1210** is located on a lowermost layer. However, the present disclosure is not limited to the above embodiment. In some embodiments, the first connection member **1110**, the second connection member **1210**, and the first and second coils **1100**, **1200** are respectively located on the first layer **310**, the second layer **320**, and the third layer **330**. In other words, the first connection member **1110** is located on the uppermost layer, the second connection member **1210** is located on the middle layer, and the first and second coils **1100**, **1200** are located on the lowermost layer depending on practical needs. In some embodiments, part of the first connection member **1110**, part of the second connection member **1210**, and the first and second coils **1100**, **1200** overlap.

In one embodiment, the first coil **1100** of the inductor device **1000** includes a first opening **400** and a third connection member **1610**, and the second coil **1200** includes a

second opening **500** and a fourth connection member **1710**. As for the structure, the third connection member **1610** is coupled to the first opening **400** of the first coil **1100**, and the fourth connection member **1710** is coupled to the second opening **500** of the second coil **1200**. For example, the third connection member **1610** is coupled to two end points **1611**, **1613** of the first opening **400** of the first coil **1100**, and the fourth connection member **1710** is coupled to two end points **1711**, **1713** of the second opening **500** of the second coil **1200**.

In addition to that, the first opening **400** is located on a first side of the first area **100** (such as an upper side of the upper half area in the figure). The third connection member **1610** is coupled to the first opening **400** of the first coil **1100** on the first side of the first area **100**. For example, the third connection member **1610** is coupled to the two end points **1611**, **1613** of the first opening **400** of the first coil **1100** on the first side of the first area **100**. In addition, the first connection member **1110** is coupled to the first circle between the outermost side and the innermost side among the first circles **110** on a second side (such as a lower side) of the first area **100**, and is coupled to the first circle on the outermost side among the first circles **110** on a second side (such as an upper side) of the second area **200**. For example, the first connection member **1110** is coupled to the first circle that is located at the middle of the three circles among the first circles **110** of the first coil **1100** on the second side of the first area **100**, and is coupled to the first circle located on the outermost side (such as a first circle **1410** (**1410-1**)) among the first circles **110** of the first coil **1100** on the second side of the second area **200**.

Additionally, the second opening **500** is located on a first side of the second area **200** (such as a lower side of the lower half area in the figure). The fourth connection member **1710** is coupled to the second opening **500** of the second coil **1200** on the first side of the second area **200**. For example, the fourth connection member **1710** is coupled to the two end points **1711**, **1713** of the second opening **500** of the second coil **1200** on the first side of the second area **200**. In addition to that, the second connection member **1210** is coupled to the second circle that is located at the first area and on the outermost side among the second circles **210** on the second side of the second area **200**, and coupled to the second circle that is located at the middle of the three circles among the second circles **210** on the second side of the second area **200**. For example, the second connection member **1210** is coupled to the second circle that is located at the first area **100** and on the outermost side among the second circles **210** of the second coil **1200**, and coupled to the second circle that is located at the second area **200** and located at the middle of the three circles (such as a second circle **1420-2**) among the second circles **210** of the second coil **1200**.

In one embodiment, the third connection member **1610** and the fourth connection member **1710** are located on a same layer. The first coil **1100** and the second coil **1200** are located on a same layer. In another embodiment, the third and fourth connection members **1610**, **1710** and the first and second coils **1100**, **1200** are located on different layers. However, the present disclosure is not limited to the above embodiment. In some embodiments, the third and fourth connection members **1610**, **1710** and the first and second coils **1100**, **1200** may have some other configurations depending on practical needs.

In another embodiment, the first coil **1100** and the second coil **1200** are collectively wound into the first turn **1410** (**1410-1**, **1410-2**), the second turn **1420** (**1420-1**, **1420-2**), and a third turn **1430** (**1430-1**, **1430-2**), and the above first

turn **1410** (**1410-1**, **1410-2**), second turn **1420** (**1420-1**, **1420-2**), and third turn **1430** (**1430-1**, **1430-2**) are sequentially arranged from an outside to an inside. The first coil **1100** is wound counterclockwise from the first side (such as a center-tapped terminal **1300** on the upper side) of the first area **100** to the second side (such as the lower side) of the first area **100** along the first turn **1410-1**, and is wound to the second turn **1420-1** on the second side of the first area **100**. The first coil **1100** is then wound from the second side of the first area **100** to the first side of the first area **100** along the second turn **1420-1**, and is wound to the third turn **1430-1** on the first side of the first area **100**. After that, the first coil **1100** is wound from the first side of the first area **100** to the first side of the first area along the third turn **1430-1**, and is coupled to the second turn **1420-1** of the first coil **1100** through the third connection member **1610**. Then, the first coil **1100** is wound from the first side of the first area **100** to the second side of the first area **100** along the second turn **1420-1**, and is coupled to the first turn **1410-1** of the first coil **1100** located at the second area through first connection member **1110**. In addition, the first coil **1100** is wound from the second side (such as the connection point **1113** on the upper side) of the second area **200** to the first side (such as an input terminal **1500** on the lower side) of the second area **200** along the first turn **1410-1**.

Additionally, the second coil **1200** is wound clockwise from the first side (such as the input terminal **1500** on the lower side) of the second area **200** to the second side (such as the upper side) of the second area **200** along the first turn **1410-2**, and is wound to the second turn **1420-2** on the second side of the second area **200**. The second coil **1200** is then wound from the second side of the second area **200** to the first side (such as the lower side) of the second area **200** along the second turn **1420-2**, and is coupled to the third turn **1430-2** through the fourth connection member **1710**. After that, the second coil **1200** is wound from the first side of the second area **200** to the first side of the second area **200** along the third turn **1430-2**, and is wound to the second turn **1420-2** on the first side of the second area **200**. The second coil **1200** is then wound from the first side of the second area **200** to the second side of the second area **200** along the second turn **1420-2**, and is coupled to the first turn **1410-2** of the second coil **1200** located at the first area **100** through the second connection member **1210**. In addition to that, the second coil **1200** is wound from the second side (such as the connection point **1211** on the lower side) of the first area **100** to the first side of the first area **100** along the first turn **1410-2**. However, the present disclosure is not limited to the structure shown in FIG. 1, which is merely used to illustrate one of the implementation methods of the present disclosure by taking an example.

FIG. 2 depicts a schematic diagram of an inductor device according to another embodiment of the present disclosure. As compared with the inductor device **1000** shown in FIG. 1, the inductor device **1000A** of FIG. 2 has a different structure at a junction of a first coil **1100A** and a second coil **1200A**. A description is provided with reference to FIG. 2. A first connection member **1110A** is coupled to a connection point **1111A** of a first circle that is located at a first area and located at a middle of three circles among first circles and a connection point **1113A** of a first circle that is located at a second area and on an outermost side among the first circles. A second connection member **1210A** is coupled to a connection point **1211A** of a second circle that is located at the first area and on an outermost side among second circles and a connection point **1213A** of a second circle that is located at the second area and located at a middle of three circles

among the second circles. In one embodiment, part of the first connection member **1110A** and part of the second connection member **1210A** overlap. In another embodiment, an area **1800A** where part of the first connection member **1110A** overlaps part of the second connection member **1210A** does not overlap the first and second coils **1100A**, **1200A**. In still another embodiment, the first connection member **1110A** and the first and second coils **1100A**, **1200A** are located on a same layer, and the first connection member **1110A** and the second connection member **1210A** are located on different layers. It is noted that, in the embodiment shown in FIG. 2, elements having the reference numbers similar to those in FIG. 1 have similar structural features. To simplify matters, a description in this regard is not provided. In addition, the present disclosure is not limited to the structure shown in FIG. 2, which is merely used to illustrate one of the implementation methods of the present disclosure by taking an example.

FIG. 3 depicts a schematic diagram of an inductor device **1000B** according to still another embodiment of the present disclosure. As compared with the inductor device **1000A** shown in FIG. 2, the inductor device **1000B** of FIG. 3 has a different structure at a junction of a first coil **1100B** and a second coil **1200B**, does not have the first opening and the third connection member **1610A**, and does not have the second opening and the fourth connection member **1710A**. A description is provided with reference to FIG. 3. A first connection member **1110B** is coupled to a connection point **1111B** of a first circle that is located at a first area and located at a middle of three circles among first circles and a connection point **1113B** of a first circle that is located at a second area and on an outermost side among the first circles. A second connection member **1210B** is coupled to a connection point **1211B** of a second circle that is located at the first area and on an outermost side among second circles and a connection point **1213B** of a second circle that is located at the second area and located at a middle of three circles among the second circles. In one embodiment, part of the first connection member **1110B** and part of the second connection member **1210B** overlap. In another embodiment, an area **1800B** where part of the first connection member **1110B** overlaps part of the second connection member **1210B** does not overlap the first and second coils **1100B**, **1200B**. In still another embodiment, the first connection member **1110B** and the first and second coils **1100B**, **1200B** are located on a same layer, and the first connection member **1110B** and the second connection member **1210B** are located on different layers.

In one embodiment, the first coil **1100B** and the second coil **1200B** are collectively wound into the first turn **1410** (**1410-1**, **1410-2**), the second turn **1420** (**1420-1**, **1420-2**), and the third turn **1430** (**1430-1**, **1430-2**), and the first turn **1410** (**1410-1**, **1410-2**), the second turn **1420** (**1420-1**, **1420-2**), and the third turn **1430** (**1430-1**, **1430-2**) are sequentially arranged from an outside to an inside. The first coil **1100B** is wound counterclockwise from a first side (such as a center-tapped terminal **1300B** on an upper side) of the first area **100** to a second side (such as a lower side) of the first area **100** along the first turn **1410-1**, and is wound to the third turn **1430-1** on the second side of the first area **100**. The first coil **1100B** is then wound from the second side of the first area **100** to the first side of the first area **100** along the third turn **1430-1**, and is wound to the second turn **1420-1** on the second side of the first area **100**. After that, the first coil **1100B** is wound from the second side of the first area **100** to the second side of the first area **100** along the second turn **1420-1**, and is coupled to the first turn **1410-1**.

of the first coil **1100B** located at the second area through the first connection member **1110B**. Additionally, the first coil **1100B** is wound from a second side (such as the connection point **1113B** on an upper side) of the second area **200** to a first side (such as a lower side) of the second area **200** along the first turn **1410-1**.

In addition to that, the second coil **1200B** is wound clockwise from the first side (such as the center-tapped terminal **1300B** on the upper side) of the first area **100** to the second side of the first area **100** along the first turn **1410-2**, and is coupled to the second turn **1420-2** of the second coil **1200B** located at the second area **200** through the second connection member **1210B**. In addition, the second coil **1200B** is wound from the second side (such as the connection point **1211B** on the upper side) of the second area **200** to the second side of the second area **200** along the second turn **1420-2**, and is wound to the third turn **1430-2** on the second side of the second area **200**. The second coil **1200B** is wound from the second side of the second area **200** to the second side of the second area **200** along the third turn **1430-2**, and is wound to the first turn **1410-2** on the second side of the second area **200**. The second coil **1200B** is wound from the second side of the second area **200** to the first side (such as the lower side) of the second area **200** along the first turn **1410-2**. It is noted that, in the embodiment shown in FIG. 3, elements having the reference numbers similar to those in FIG. 2 have similar structural features. To simplify matters, a description in this regard is not provided. Additionally, the present disclosure is not limited to the structure shown in FIG. 3, which is merely used to illustrate one of the implementation methods of the present disclosure by taking an example.

As shown in FIG. 1, when a voltage is inputted from the input terminal **1500**, a left-sided terminal of the input terminal **1500** receives a positive voltage, and a right-sided terminal of the input terminal **1500** receives a negative voltage. At this time, the circles presented by a dotted mesh are at a same potential (such as the positive voltage), and the circles presented by a slashed mesh are at a same potential (such as the negative voltage). A description is provided with reference to the horizontal dotted line in the lower half area of the inductor device **1000** shown in the figure. It can be seen from the horizontal dotted line that most of the coils in the second area are at a same potential because the same coil (such as the second coil **1200**) is mostly wound in the second area **200**. Accordingly, the inductor device **1000** only generates parasitic capacitance at a position where the first turn **1410** is adjacent to the second turn **1420** on a rightmost side of the horizontal dotted line. As compared with a typical eight-shaped inductor device in which parasitic capacitances are generated at positions where most of the circles are adjacent to one another, the inductor device **1000** according to the present disclosure can indeed reduce the parasitic capacitance to improve the quality factor of the inductor device **1000**. It is noted that the inductor devices **1000A** to **1000B** of FIG. 2 to FIG. 3 according to the present disclosure have a same structural configuration as that of the inductor device **1000** shown in FIG. 1. As a result, the inductor devices **1000A** to **1000B** can similarly reduce the parasitic capacitance to improve the quality factor of the inductor devices **1000A** to **1000B**.

FIG. 4 depicts a schematic diagram of experimental data of the inductor devices **1000** to **1000B** shown in FIG. 1 to FIG. 3 according to some embodiments of the present disclosure. As shown in the FIG. 4, curve **C1** is the experimental data of quality factor of a typical eight-shaped inductor device. If the structural configuration of the present

disclosure is adopted, the experimental data of quality factor is curve **C3**. As can be seen from FIG. 4, the inductor device **1000** adopting the structure shown in FIG. 1 of the present disclosure has a better quality factor. For example, at a frequency of 10 GHz, the quality factor of the curve **C1** is about 11, but the quality factor of the curve **C3** according to the present disclosure is about 13. It is thus understood that the quality factor of the inductor device **1000** according to the present disclosure is indeed better. In addition to that, curve **L1** shows the inductance value of a typical eight-shaped inductor device, and its self-resonant frequency is about 22 GHz. Since the frequency where the self-resonant frequency occurs is closer to the peak of the quality factor of the curve **C1**, it will have a greater impact on the quality factor. In addition, as can be seen from FIG. 4, the flat range before the point at which the curve **L1** starts to rise is shorter, which in turn causes a smaller operable range. As for the inductance value represented by curve **L3** of the inductor device **1000** having the structure shown in FIG. 1 according to the present disclosure, its self-resonant frequency is about 29 GHz. In comparing, since the frequency where the self-resonant frequency occurs is farther from the peak of the quality factor of the curve **C3**, its effect on the quality factor is smaller. Additionally, as can be seen from FIG. 4, the flat range before the point at which the curve **L3** starts to rise is longer, so that the operable range is wider.

It can be understood from the embodiments of the present disclosure that application of the present disclosure has the following advantages. The inductor device according to the embodiments of the present disclosure can effectively reduce the parasitic capacitance between the coils of the inductor device so as to allow the inductor device to have a better quality factor (Q). In addition, the frequency where the self-resonant frequency (Fsr) of the inductor device occurs is effectively improved to move the frequency where the self-resonant frequency occurs to a higher frequency, thus reducing the influence on the quality factor.

Although the present invention has been described in considerable detail with reference to certain embodiments thereof, other embodiments are possible. Therefore, the spirit and scope of the appended claims should not be limited to the description of the embodiments contained herein.

It will be apparent to those skilled in the art that various modifications and variations can be made to the structure of the present invention without departing from the scope or spirit of the invention. In view of the foregoing, it is intended that the present invention cover modifications and variations of this invention provided they fall within the scope of the following claims and their equivalents.

What is claimed is:

1. An inductor device, comprising:
a first coil comprising a first connection member and a plurality of first circles, wherein at least two first circles of the first circles are located at a first area, and half of the first circle of the first circles is located at a second area and coupled to an input terminal at the second area; and
a second coil comprising a second connection member and a plurality of second circles, wherein at least two second circles of the second circles are located at the second area, and half of the second circle of the second circles is located at the first area and coupled to the first coil at the first area, wherein the first connection member is coupled to the first circle between an outermost side and an innermost side among the first circles that are located at the first area and half of the first circle of the first circles that are located at the

second area, wherein the second connection member is coupled to the half of the second circle of the second circles that are located at the first area and the second circle between an outermost side and an innermost side among the second circles that are located at the second area.

2. The inductor device of claim 1, wherein part of the first connection member and part of the second connection member overlap.

3. The inductor device of claim 1, wherein the first connection member and the second connection member are located on different layers.

4. The inductor device of claim 1, wherein the first coil and the second coil are located on a same layer.

5. The inductor device of claim 4, wherein the first connection member is located on a first layer, the first coil and the second coil are located on a second layer, and the second connection member is located on a third layer.

6. The inductor device of claim 5, wherein the first layer, the second layer, and the third layer are sequentially stacked.

7. The inductor device of claim 4, wherein the first connection member is located on a first layer, the second connection member is located on a second layer, and the first coil and the second coil are located on a third layer.

8. The inductor device of claim 7, wherein the first layer, the second layer, and the third layer are sequentially stacked.

9. The inductor device of claim 4, wherein part of the first connection member, part of the second connection member, the first coil, and the second coil overlap.

10. The inductor device of claim 1, wherein the first coil comprises a first opening and a third connection member, the second coil comprises a second opening and a fourth connection member, wherein the third connection member is coupled to the first opening of the first coil, and the fourth connection member is coupled to the second opening of the second coil.

11. The inductor device of claim 10, wherein the first opening is located on a first side of the first area, and the third connection member is coupled to the first opening of the first coil on the first side of the first area.

12. The inductor device of claim 11, wherein the first connection member is coupled to the first circle between the outermost side and the innermost side among the first circles on a second side of the first area, and is coupled to the first circle on the outermost side among the first circles on a second side of the second area.

13. The inductor device of claim 12, wherein the second opening is located on a first side of the second area, and the fourth connection member is coupled to the second opening of the second coil on the first side of the second area.

14. The inductor device of claim 13, wherein the second connection member is coupled to the second circle on the outermost side among the second circles on the second side of the first area, and is coupled to the second circle between the outermost side and the innermost side among the second circles on the second side of the second area.

15. The inductor device of claim 10, wherein the third connection member and the fourth connection member are located on a same layer, and the first coil and the second coil are located on a same layer.

16. The inductor device of claim 15, wherein the third connection member and the fourth connection member are located on a different layer from the first coil and the second coil.

17. The inductor device of claim 10, wherein the first coil and the second coil are collectively wound into a first turn, a second turn, and a third turn, wherein the first turn, the

second turn, and the third turn are sequentially arranged from an outside to an inside, wherein the first coil is wound from a first side of the first area to a second side of the first area along the first turn, and is wound to the second turn on the second side of the first area, the first coil is then wound from the second side of the first area to the first side of the first area along the second turn, and is wound to the third turn on the first side of the first area, the first coil is thereafter wound from the first side of the first area to the first side of the first area along the third turn, and is coupled to the second turn of the first coil through the third connection member, the first coil is then wound from the first side of the first area to the second side of the first area along the second turn, and is coupled to the first turn of the first coil located at the second area through first connection member, wherein the first coil is wound from a second side of the second area to a first side of the second area along the first turn.

18. The inductor device of claim 17, wherein the second coil is wound from the first side of the second area to the second side of the second area along the first turn, and is wound to the second turn on the second side of the second area, the second coil is then wound from the second side of the second area to the first side of the second area along the second turn, and is coupled to the third turn through the fourth connection member, the second coil is thereafter wound from the first side of the second area to the first side of the second area along the third turn, and is wound to the second turn on the first side of the second area, the second coil is then wound from the first side of the second area to the second side of the second area along the second turn, and is coupled to the first turn of the second coil located at the first area through the second connection member, wherein the second coil is wound from the second side of the first area to the first side of the first area along the first turn.

19. The inductor device of claim 1, wherein the first coil and the second coil are collectively wound into a first turn, a second turn, and a third turn, wherein the first turn, the second turn, and the third turn are sequentially arranged from an outside to an inside, wherein the first coil is wound from a first side of the first area to a second side of the first area along the first turn, and is wound to the third turn on the second side of the first area, the first coil is then wound from the second side of the first area to the second side of the first area along the third turn, and is wound to the second turn on the second side of the first area, the first coil is thereafter wound from the second side of the first area to the second side of the first area along the second turn, and is coupled to the first turn of the first coil located at the second area through the first connection member, wherein the first coil is wound from a second side of the second area to a first side of the second area along the first turn.

20. The inductor device of claim 19, wherein the second coil is wound from the first side of the first area to the second side of the first area along the first turn, and is coupled to the second turn of the second coil located at the second area through the second connection member, wherein the second coil is wound from the second side of the second area to the second side of the second area along the second turn, and is wound to the third turn on the second side of the second area, the second coil is wound from the second side of the second area to the second side of the second area along the third turn, and is wound to the first turn on the second side of the second area, the second coil is wound from the second side of the second area to the first side of the second area along the first turn.
